UNITED STATES PATENT OFFICE.

LORAN A. WIGGINS, OF MILWAUKEE, WISCONSIN.

CONVERTIBLE COOKING-CABINET.

1,216,030.

Specification of Letters Patent. Patented Feb. 13, 1917.

Application filed December 16, 1915. Serial No. 67,114.

To all whom it may concern:

Be it known that I, LORAN A. WIGGINS, a citizen of the United States, and resident of Milwaukee, in the county of Milwaukee and State of Wisconsin, have invented certain new and useful Improvements in Convertible Cooking-Cabinets; and I do hereby declare that the following is a full, clear, and exact description thereof.

10 The present invention relates to new and useful improvements in cabinets and is more particularly directed to the provision of a cabinet adapted to contain a stove.

It is the object of the present invention to 15 provide such a cabinet wherein a stove may be positioned for ordinary cooking operations and which is provided with parts adapted to conceal the stove whereby the cabinet may assume the appearance of a 20 stand or similar article of furniture, it being more particularly an object to provide such a structure wherein the portion of the cabinet which serves to conceal the stove also serves when at extended position to expose the 25 stove, as a shield member to prevent marring of a wall, against which the cabinet might be placed, by food stuffs on the stove.

A further object resides in the provision 30 of a cabinet member of the type described which is comparatively simple in structure and which may be readily disassembled for cleaning.

With the above and other objects and advantages in view, the invention resides more 35 particularly in the novel combination, arrangement and formation of parts more particularly hereinafter described and particularly pointed out in the appended claims.

In the drawings:

40 Figure 1 is a perspective view of the cabinet with the stove compartment thereof closed.

Fig. 2 is a horizontal sectional view taken 45 through the stove compartment of the cabinet.

Fig. 3 is a vertical sectional view showing the cover of the stove compartment closed, the open position of this cover being indicated in dotted lines.

50 Referring now more particularly to the accompanying drawings, the cabinet is shown as comprising side walls 5, a back wall 6 and a main partition wall 7 disposed in the upper portion of the cabinet and dividing it into a body compartment 8 having shelves 9 for carrying dishes or other

articles, and into a stove compartment, in which is disposed preferably a gas stove 10 of a conventional small type. The front of the body compartment is closed by suitable hinged doors 11 and the front of the stove compartment is closed by a detachable panel 12. The top of the partition 7 and the inner faces of the vertical walls are faced with sheets of asbestos 13, to prevent burning of the 65 cabinet by heat given off by the stove, and to provide a sanitary and easily cleaned structure a sheathing of metal 14 is disposed over the asbestos. The panel 12 is also provided with a facing 15 of asbestos over 70 which is disposed a metal plate 15' and to provide for the securement of the panel 12, the ends of the metallic plate are extended past the ends of the panel 12 and are slidably disposed in grooves formed by inwardly extending portions of forward corner uprights 16 of the side walls 5 and by inturned edge portions 17 of the adjacent metal sheathing of the walls.

Thus the panel 12 may be lifted from the 80 cabinet and the stove compartment very readily cleaned. For concealing the stove compartment when it is not in use, a top 18 is provided for said compartment and is hinged to the back wall 6 and adapted to 85 swing to a vertical position and to be normally held in such position by toggle links 19 connected therewith and with the side walls.

When in this vertical position the cover 90 member serves as a back board for the stove to prevent damage caused by spattering of food on the stove. The member carries adjacent its free edge a ledge or shelf 20 which serves to support articles over the stove 95 when the member is in vertical position. When the member is swung to closing position this ledge 20 extends between the stove and the panel 12, it being noted that the stove is positioned rearwardly in the compartment to permit such disposal of the shelf and also to permit ready manipulation of the valves of the stove. The shelf 20 in its closed position serves to hold the stove against the back of the compartment. 100 105

The inner face of the member 18 and the bottom of the ledge 20 are preferably provided with a metal sheathing 21.

For conveying fuel to the stove a tube 22 is extended from the stove through one of 110 the side walls 5 to a suitable source of fuel.

A simple and compact device is thus pro-

vided which facilitates normal cooking operations in conjunction with the stove disposed therein and which may be arranged to entirely conceal the stove whereby the entire device may assume the appearance of an ordinary stand or cabinet not necessarily associated with culinary operations.

The present cabinet finds its most particular application in small apartments in connection with what is usually termed "light house keeping."

The stove used in connection with the present cabinet has been shown and described as a gas stove, but it is not desired to limit the present invention in this connection as any compact form of stove could be utilized and in many instances an electric stove would be found preferable. In the use of an electric stove, suitable feed wires would extend therefrom in the manner of the fuel tube 22.

I claim:

1. A cabinet including an upper compartment comprising front and rear and side walls and a bottom, a stove disposed in the rear portion of the compartment whereby a space is formed between said stove and the front wall, a cover for the compartment

hinged to the rear wall and a shelf member extending laterally from the inner face of the cover and adapted to lie between the stove and the front wall of the compartment upon folding the cover, whereby the stove is held against movement forwardly in the compartment.

2. A cabinet including an upper compartment including side walls having inwardly directed front portions, a metallic sheathing on the bottom and walls of the compartment, the ends of the sheathing adjacent said inward front portions of the side walls being directed inwardly to form grooves therewith, a front wall panel for the compartment, and a sheathing plate on the panel having its edges extending beyond the ends of the panel to slidably engage in the grooves, and a cover for the compartment.

In testimony that I claim the foregoing I have hereunto set my hand at Milwaukee, in the county of Milwaukee and State of Wisconsin, in the presence of two witnesses.

LORAN A. WIGGINS.
